UNITED STATES PATENT OFFICE.

GRANT E. ALLEMAN, OF SHOEMAKERSVILLE, PENNSYLVANIA, ASSIGNOR OF ONE-HALF TO THE FIRM OF ALLEMAN & WOLFE (GRANT E. ALLEMAN AND DAVID S. WOLFE) AND ONE-HALF TO THE FIRM OF ALLEMAN & EBERSOLE (GRANT E. ALLEMAN AND JOHN M. EBERSOLE), BOTH OF SHOEMAKERSVILLE, PENNSYLVANIA.

COAL AND SAND RECLAIMING DEVICE.

1,165,379.

Specification of Letters Patent. Patented Dec. 28, 1915.

Application filed May 14, 1914. Serial No. 838,498.

To all whom it may concern:

Be it known that I, GRANT E. ALLEMAN, a citizen of the United States, residing at Shoemakersville, in the county of Berks and 5 State of Pennsylvania, have invented certain new and useful Improvements in Coal and Sand Reclaiming Devices, of which the following is a specification.

My invention relates to machines for segregating substances of differing form and character from that of which they are components, and is directed particularly to such mechanism as is especially designed for separating such substances as may be carried by 15 a fluid vehicle.

The principal objects of my invention are, to provide mechanism for segregating coal, sand, stones and debris from semi-aqueous sludge, taken from the bed of rivers, creeks 20 and such streams as may contain coal sediments, in such quantities as it may be found commercially profitable to reclaim; to provide means for so controlling the fluid vehicle as to insure complete and thorough 25 cleansing of the coal and sand; and to provide means for separately collecting said coal and sand and discharging the water, stones and other undesirable debris.

Other objects of my invention, specifically 30 stated, are to provide a machine with means whereby the undesirable debris is initially eliminated; to provide means to retard the flow of water for washing purposes; and to provide means for so controlling the sand 35 that only sufficient water may be admitted therewith to the conveyer trough as may form a vehicle therefor.

My invention further includes all of the various novel features of construction and 40 arrangement of the parts as may be hereinafter more specifically specified.

In the accompanying drawings, Figure 1 is a sectional side elevational view of a coal and sand reclaiming machine constructed in 45 accordance with my invention, the section being taken longitudinally of the inlet trough on the line 1—1 in Fig. 2; Fig. 2 is a sectional view taken at right angles to the section shown in Fig. 1, on the line 2—2 in

said figure, and extending longitudinally 50 through the screening trough and the sand discharging trough or conveyer, the sieve being shown in elevation for convenience of illustration; Fig. 3 is a fragmentary side elevational view of the discharge end of the 55 sieve frame; Fig. 4 is a vertical transverse sectional view of said sieve frame, taken on the line 4—4 in Fig. 3, the sprocket being removed for convenience of illustration; and Fig. 5 is a vertical transverse sectional view 60 of the sieving trough *per se*, showing the actuating handle for the valves which control the outlet aperture in the floor thereof through which the sand is permitted to escape at suitable intervals. 65

In said figures, the conveyer nozzle 1 of a dredge (not shown) is arranged to direct aqueous sludge containing coal, sand, etc., into the inlet trough 2 and upon the reticulated false bottom 3 through which the water 70 passes to the floor of the trough 2, the solid substances being directed onto the swinging cradle comprising the reciprocatory screen 4, suspended by links 5 and 6 which are pivoted to the standards 7 and 8. 75

The undesirable debris is shunted from the cradle onto the discharging apron 9, which extends outwardly from the unreticulated false bottom 10 of the trough 2, said false bottom 10 having the intervening 80 scooped spout 11 for directing the screenings, comprising coal and sand, into the rotary sieve 12, which has the shaft 13 mounted to rotate in bearings in the walls 14 and 15. 85

The cradle is connected to be rocked by the link 16 to the eccentric 17 on the driving shaft 18, which is mounted in suitable bearings in the standard 19. Said shaft 18 is connected by the sprocket 20 and chain 21 90 with the sprocket 22 on the sieve 12, to rotate the latter.

Subjacent to the rotary sieve 12, and connected with the discharge end of the trough 2, is a screening trough or elongated reservoir 24 having the partitions 25, 26 and 27 forming the compartments 28, 29, 30 and 31, the compartment 28 being arranged to re- 95

ceive the water from the trough 2, and the compartments 29, 30 and 31 being arranged to receive the screenings from the rotary screen 12. The compartment 28 has the uncontrolled outlets 32, but is provided with the baffle plate or partition 33 to prevent the direct flow of water to said outlets. The compartments 29, 30 and 31 are provided with outlets 35, 36 and 37, respectively controlled by valves 38, 39 and 40, which may be actuated in any desired manner, as by the handle 41 shown in Fig. 5.

The outlets of the respective compartments 29, 30 and 31 are provided with outlet spouts 43, 44 and 45 opening into the trough or conduit 46 which is subjacent to the screening reservoir 24 and through which the water from the chamber 28 is carried. Said spouts have their discharge ends directed in the direction of the flow of the water in the trough 46 and are slightly inclined downwardly toward their discharge ends.

The partitions 25, 26 and 27 are for the purpose of retarding the flow of water, and the partitions 25 and 26, as shown in Fig. 2, are provided with suitably disposed apertures for permitting the escape of sand therethrough before it reaches an undesirable level.

The water passing through the reservoir, serves to cleanse the contents of the screen of all soluble matter and smaller particles, such as sand. A certain quantity of such particles are caught in each compartment, and, in order to prevent choking or stalling of the machine, the partitions are perforated to permit the water to carry along such particles after they attain the height of the perforations. When it is desired to flush the compartments, the lever 41 is actuated to open wide the outlets 35, 36 and 37, whereby the compartments are cleansed of these particles of sand and this sand may be redeemed as it emerges from the end of the trough 46.

As shown in Fig. 2, the chamber 31 is provided with an overflow outlet 49 in the side wall thereof to prevent the water which may collect in said chamber from overflowing into the outlet trough 50 for conveying the coal from the screen 12. The trough 50 is inclined upwardly toward its outlet end, and is provided with a false bottom which comprises the substantially semi-cylindrical portion 51, preferably formed of unreticulated sheet metal, and a reticulated portion 52 extending therefrom parallel with the bottom wall of said trough to its outlet end.

The coal is discharged from the outlet end of the screen 12 into the semi-cylindrical end of the false bottom of the outlet trough 50, and is conveyed upwardly and discharged therefrom by the conveyer chain 53 having

blades or fins 55 extending substantially the full width of the trough and dragging upon said false bottom. The conveyer chain 53 is carried by the sprocket 56 on the screen 12, by which it is driven, and by the sprocket 57 which is mounted in bearings 58 on the trough 50.

The screen 12, as best shown in Fig. 3, comprises the head ring 59 and intermediate rings 60 joined by the longitudinal bars 62, upon which are carried the angularly disposed wings 63, which are arranged upon diametrically opposite sides of said screen and project inwardly, the wings upon one side being inclined opposite to those on the other side so as to tend to shift the coal toward the discharge end. The head ring 59 is connected with the shaft 13 by the spider frame 65, which is formed of a central hub 66 embracing the shaft 13 and connected with the head by brackets 67 formed of strap metal.

The machine above described is preferably supported by suitably disposed standards 71, and carried by a float 72 which may conveniently follow the dredge to receive the sludge pumped up thereby, and the separated screening may be directly discharged into suitably disposed barges.

I do not desire to limit my invention to the precise details of construction and arrangement herein set forth, as it is obvious that various modifications may be made therein without departing from the essential features of the invention as defined in the appended claims.

Having thus described my invention, I claim:

1. In coal and sand separating mechanism, the combination with a rotary screen, of a subjacent reservoir divided into compartments each having outlets, a baffle board extending partly across the first compartment, an inlet trough leading into said first compartment, a false bottom in said trough terminating short of the initial end of said trough, and having a spout directed into said screen, a reticulated false bottom extended from the initial end of said trough, a conduit subjacent to said reservoir, into which said outlets open, a separate spout for the outlets of the respective compartments, and an outlet trough for conveying the discharge from the end of said screen.

2. In coal and sand separating mechanism, the combination with a rotary screen, of a subjacent reservoir having partitions forming compartments, respectively provided with outlet apertures, certain of said partitions having perforations forming communication between adjacent compartments, a baffle board in the first compartment, an inlet trough leading into said first compartment, means for controlling the outlets of

the respective compartments, a conduit common to the outlets of all of said compartments, and a false bottom for said inlet trough, comprising a reticulated portion and 5 a plain portion having a spout leading into said screen.

In testimony whereof I affix my signature in presence of two witnesses.

GRANT E. ALLEMAN.
